PIVOTAL FRAME MOUNTING STRUCTURE
FOR OFFSET PRINTING MACHINE CYL-
INDERSLawrence H. Morse, Mentor, Ohio, assignor to
Addressograph-Multigraph Corporation, Cleve-
land, Ohio, a corporation of DelawareOriginal application April 19, 1946, Serial No.
663,517, now Patent No. 2,525,931, dated Octo-
ber 17, 1950. Divided and this application Jan-
uary 15, 1948, Serial No. 2,499

7 Claims. (Cl. 101—177)

1

This application is a division of my pending application No. 663,517, filed April 19, 1946, which has matured into Patent No. 2,525,931, granted October 17, 1950, for a printing machine, and relates to an offset printing machine having a plurality of pattern rolls coacting with a single offset roll, whereby imprints may be made in a plurality of colors.

The invention is well adapted for use in a machine such as set out in detail in my parent application showing four pattern rolls and two offset rolls, one pair of pattern rolls coacting with one of the offset rolls, the other pair with the other offset rolls and the two offset rolls coacting with each other so that each may perform the function of a platen for an opposed offset roll. To prevent such offset rolls from offsetting on each other, it is necessary that they be separated at all times except when a sheet of paper is passing between them. Therefore, one or the other of the offset rolls must be shiftably mounted. Since the pattern roll or rolls from which the image is offset to the paper, must be kept in correct registration with the offset roll to maintain a clear image, it becomes necessary to move it or them, also, and in a proper fashion to preserve such registration.

An object of the present invention is to provide means whereby the various rolls are separately mounted for individual movement relative to the machine frame, and whereby such movements may be correlated to preserve the registration. This object is accomplished by providing separate frames for the movable offset roll and for each of its pattern rolls and associated inking mechanism. These frames are individually hinged to the main machine frame and are interconnected with a linkage for the proper control of their movement.

Other objects and advantages in the present invention will be apparent from the accompanying drawings and the following description thereof.

In the drawings, Fig. 1 is a side elevation of an offset printing machine embodying my invention; Fig. 2 is a plan thereof; Fig. 3 is a fragmentary elevation looking in the direction opposite to Fig. 1 and showing the mechanism for moving the upper offset roll; Fig. 4 is a vertical section in a plane parallel with Fig. 1 and on a much larger scale illustrating the paper detecting device; Fig. 5 is a detail view in vertical section illustrating a device for separating the pattern rolls from their respective offset roll; Fig. 6 is a transverse section taken on the plane 6—6 in Fig. 5.

2

In the embodiment of my invention, as illustrated particularly in Fig. 1 of the drawing, I have provided a printing machine having two offset rolls, the lower one 10 of which has a shaft 5 fixedly carried by the main frame F, and the upper one 11 of which is carried by a springing carrier comprising side plates 12 pivoted at 13 on the frame. The offset rolls are adapted to print upon opposite sides of a sheet which is delivered to the machine, by mechanism indicated conventionally at 14, and is fed to the rolls at the proper time by a paper feed and detecting mechanism indicated generally at 15. After printing, the sheet is delivered from the machine by an ejecting device 16.

Each offset roll may transfer a two-color image from two pattern rolls. The lower offset roll 10 receives a black image, for example, from the pattern roll 20 and a red image from the pattern roll 21, and the roll 11 receives its two colors from pattern rolls 22 and 23.

Each pattern roll is provided with an inking mechanism, the roll mounting and the inking mechanism comprising a unitary structure. For 25 reasons of simplicity in manufacture and in servicing, these structures in the case of the four pattern rolls may be identical. As shown, each pattern roll is carried by a swinging frame comprising two side plates 25 and 26 which are pivoted at 27 on the main frame F. In the case of the lower two pattern rolls, they are supported by link blocks 28, which may have eccentric mountings (Fig. 5) on the frame. In the case of the upper two pattern rolls, the side plates are similarly pivoted to the main frame but are supported by 35 means of adjustable links 30 and 31 which tie them to the side plates 12 of the offset roll carrier.

To separate the offset rolls when the machine 40 is not printing or when a sheet is inadvertently absent at the feeding position, I provide a separating mechanism, shown in detail in Fig. 3 and hereinafter described, which is adapted to raise and lower the offset roll carrier 12 by turning an eccentric shaft which supports the carrier.

To drive the various rolls and to preserve their proper registration, each of the offset and pattern rolls is provided with a gear 36 whose pitch diameter is equal to the diameter of the roll. 45 The gear which is associated with the lower offset roll is power driven by suitable mechanism terminating in a gear 136 (Fig. 1) meshing with that gear 36.

Referring now to Fig. 4, it will be noted that 50 as a sheet S enters on the feeding mechanism 44

it is guided by plates 37 and 38 into the bite of a pair of feed rollers 39 and 40 which, in turn, move it into the bite of the offset rolls 10 and 11. Normally, the rollers 39 and 40 are separated so that no driving occurs, and a series of stop fingers 41 stand across the path of the paper, as indicated in broken lines at 41'. The leading edge of the sheet engages the fingers until, at the proper time in the cycle, the fingers are withdrawn and the feed rollers are engaged to move 10

The upper roller 39 comprises a series of spaced sections, as shown in Fig. 4, on a shaft 42 carried in bearings on the main frame and provided with a gear 43. The gear is constantly driven from 15 the gear 36 of the offset roll 11 through an idler 44.

The lower roller 40 is adjustably mounted, as indicated at 45, on a swinging frame 46 pivoted at 47 on the main frame F. The frame 46 carries a cam follower 48 which constantly engages a large disc cam 49 on the lower offset roll 10. The cam is provided with a short raised dwell 50 which, at the proper time in the rotation of the roll, is adapted to swing the frame 46 upwardly to press the roller 40, and hence the sheet S, against the rotating driving roller 39.

The frame 46 also carries an angularly adjustable extension 51 which bears against the supporting block 52 of the stop fingers. When the carrier 46 is rocked upwardly by the cam 49 the extension rocks the bar 52, against the action of a light tension spring 53, to withdraw the stop fingers immediately before the sheet is thrown forwardly by the feed rollers.

The presence of the sheet is detected by a feeler 55 which is carried by a shaft 56 and rests upon the paper. The sheet bridges a groove 57 in the feed roller 40 and, in the absence of a sheet, the feeler drops into the groove. The angular position of the shaft 56 is thus dependent upon the presence or absence of a sheet in feeding position and is adapted to control the raising and lowering of the upper offset roll, as will next be described.

As best seen in Fig. 3, the angular position of each of the side plates 12 of the upper offset roll carrier about its pivot 13 is determined by a support comprising a link 60. A cross shaft 61, having bearings in the main frame F, is provided with an eccentric portion 62 which pivotally supports the links. Rotation of the shaft is thus adapted to raise and lower the carrier to alter the spacing of the offset rolls 10 and 11. Normally the shaft is turned to roll separating position by means of a tension spring 63 which is anchored to the main frame at 64 (Fig. 2) and which urges counter-clockwise a block 65 adjustably secured at 66 to a plate 67 which, in turn, is drivingly secured to the shaft.

Mechanism is provided whereby the shaft 61 is turned to lower the offset roll 11 to printing position during the non-printing portion of each cycle of the machine and whereby the presence or absence of a sheet in feeding position determines whether the roll remains in position to act upon the sheet, or whether it is again raised before the printing portion of the cycle commences, to prevent offsetting upon the other roll in the absence of a sheet. A bell crank 70 is pivoted at 71 on the main frame and is linked at 72 to the block 65. A cam follower 73 on the bell crank coacts with a cam 74 on the shaft of the lower offset roll 10 and, at the proper time in each cycle, a rise 75 on the cam lifts the bell

crank to rock the block 65 in a clockwise direction to lower the roll 11.

The cam follower 73 may be hinged, as shown on the bell crank whereby it may be idly swung out of the way when the cam 74 is rotated in the opposite direction, as during manual manipulation of the machine during the initial registration of the rolls.

The bell crank 70, having been raised to roll engaging position shown, is retained in such position when a sheet is properly present in the machine. The feeler shaft 56, previously mentioned, is provided with an arm 76, and the bell crank 70 carries an adjustable shoulder 77. When a sheet is absent, a spring, not shown, urges the feeler 55 downwardly into the groove of the feed roller 40 and swings the arm 76 in the direction of the arrow to idle position. As the rise 75 of the cam then leaves the cam follower, the spring 63 and a second spring 78 are free to rock the bell crank and the block 65 back to roll separating position. A sheet present at printing position, however, lifts the feeler and the arm 76 is swung to the position shown. As the shoulder 77 is lowered by the action of the cam 74, the arm is sprung aside, against the action of a light tension spring 76', and then snaps into the shoulder. The shoulder is prevented thereby from rising and the offset rolls are prevented from separating.

The offset rolls 10 and 11 are constructed with the usual gaps in their peripheries which provide for the attaching devices for their offsetting blankets. As indicated in Fig. 3, the positioning of the rolls occurs at a time in the cycle when their two gaps are in registration and before the leading edges 79 of their offset surfaces come into engagement.

Each of the side plates 12 of the offset roll carrier is individually hinged to the frame at 13 and each has an adjustable eccentric connection 80 with its respective supporting link 60. Differential raising or lowering of the two sides may thus be obtained in the initial adjustment for uniformity of printing pressure along the line of printing contact.

A dashpot 82 may be provided to prevent the shock which might be occasioned, when the bell crank 70 and its associated parts are released by the cam 74. The dashpot may be interposed, as shown, between the bell crank and a pivotal anchorage on the main frame at 83 and may be controlled by a valve 84.

As previously mentioned, each pattern roll is carried by a pair of side plates 25 and 26 which are pivoted to the main frame at 27. In the case of the roll 22, the side plates, as best shown in Figs. 1 and 2, are supported about their pivots by a pair of links 30 which extend from the shaft of the roll to the shaft of the upper offset roll. The links may be of the nature of turnbuckles as shown, whereby the shaft spacings at the front and the rear of the machine may be altered to obtain the required uniformity of contact of the rolls. As the upper offset roll is raised and lowered by the mechanism of Fig. 3, the pattern roll is thus rocked about the pivots 27 and the continued meshing of the gears 36 of the two rolls preserves proper registration.

The case of the upper pattern roll 23 is somewhat simpler in that the pivots 27 of its side plates may coincide with the pivots 13 of the upper offset roll carrier 12 (Figs. 1, 2, 8 and 13). Thus, by interconnecting the ends of the roll shaft with the side plates 12 by means of a pair

of links or turnbuckles 31, there is produced, in effect, an integral structure. This structure is simply rocked around the pivot 13-27 by the raising and lowering mechanism of Fig. 3, and the proper registration of the two rolls is at all times preserved.

When the machine is standing idle or when the blankets or plates are to be changed, it is necessary to withdraw the pattern rolls from the offset rolls to prevent injury of the surfaces. In the case of the lower two rolls 20 and 21 this is accomplished by rocking the side plates about their pivots 27. As previously mentioned, each plate is supported by a link 28. As best seen in Figs. 5 and 6, the links are pivotally supported on the eccentric portion 85 of a shaft 86 which extends across the main frame. When the shaft is oscillated the links move up and down to engage and disengage the pattern roll with the offset roll. The shaft is maintained in roll-engaging position by means of a block 87 which is pinned to the shaft and which carries a pivoted dog 88. The dog is spring pressed into contact with the face of a disc 89, adjustably secured to the main frame, and, at the proper angular position of the shaft, it snaps into a notch 90 in the disc.

A handle 91 is provided to withdraw the dog from the notch and thereafter to turn the shaft. The handle is freely rotatable on the end of the shaft and has a limited angular movement relative to the block 87 by reason of a pin and slot connection at 92. The dog 88 is provided with a beveled extension 93 which is engaged by a beveled portion 94 of the handle during the first portion of the movement of the latter. Thus a clockwise movement of the handle from the position illustrated in Fig. 6 serves first to withdraw the dog from the notch and then to turn the block 87 and the shaft. When the block reaches a stop lug 95 on the disc, the links 28 are lowered sufficiently to withdraw the pattern roll. The side plates 25 and 26 are individually positionable with respect to their links 28 by reason of eccentric bushings 96 having handles 97 for manual adjustment and clamping nuts 98 to retain the bushings in adjusted position.

Separation of the pattern rolls 22 and 23 from the upper offset roll is accomplished by turning the eccentric center shafts 100 of the pattern rolls. The shafts are rotatable in bearings in the side plates 25 and 26 and the rolls rotated on ball bearings on an intermediate eccentric portion of the shaft corresponding to that at 85 of the shaft 86 just described. Each of the shafts 100 may be provided with a handle and positioning device comprising parts identical with those at 87 through 95 (Figs. 5 and 6) and some of the same reference characters have been repeated on Fig. 2.

Each of the rolls may be removed from its shaft for servicing and for replacement of the printing surface. As shown, each shaft carries a drum and this drum is embraced by a removable shell, the drum with the shell constituting a printing roll. The shells are adapted to be removed from the drum without disturbing the drums or shafts. Each shell is made for only a portion of a cylinder and the open gaps are adapted to allow the three lower drums to be removed endwise across the frame brackets which carry the shafts in drums. On the other hand, the three upper drums may be so formed with relation to their shells, that the latter can be removed radially upward after being released from their drums. These features, however, are

not claimed herein but in my parent application previously mentioned.

Suitable inking mechanism is provided for each of the pattern rolls. The particular form of such inking mechanism is immaterial. So far as shown in the drawings the mechanism for each pattern rolls comprises a series of rollers to conduct ink from a fountain roll 110, aligned with and operated by a properly turned ratchet wheel 111, suitable ductor 112 and distributing rolls 113 to carry the ink from the fountain roll to the respective patterns.

With a sheet properly positioned in the feeding and detecting device 15, and with the upper offset roll in printing position, continued operation of the machine will project the sheet into the space caused by the gaps in the offset rolls. The rolls, in the meanwhile, are revolving and the leading edges of their offset blankets B engage the sheet at some point beyond its leading edge. The two-color images are then transferred to both sides of the sheet and, due to the tackiness of the ink, the sheet adheres usually to one or the other of the offset blankets. A series of stripping fingers 120 is mounted in each offset roll whereby the sheet, instead of continuing with the roll, will be directed to the ejecting device 16.

The ejecting or delivering device 16 may be of any desired form. So far as shown it comprises a frame which carries an upper and lower series of endless tapes 125 between which the sheet is moved to the exterior of the machine.

As previously mentioned, each of the offset rolls and each of the pattern rolls is provided with a gear 36. These gears are in constant mesh with each other, the separation, formerly referred to, of the offset rolls and of the pattern rolls from the respective offset rolls being of insufficient extent to entirely withdraw the teeth. The lower offset roll 10 is power driven and serves to drive the others.

It will be seen that my machine is very compact, hence may be comparatively small for the work accomplished. Simple means are provided for separating the different rolls from each other without disturbing their individual adjustment. Such separation prevents clogging from the drying of ink and allows the ready cleaning of the rolls, and may also be employed as to some of the rolls when it is desired to print only one color on one or on both sides of the sheet or desired to print in one or two colors on one side only.

I claim:

- 55 1. In a printing machine, the combination with a main frame, a platen carried thereby, a supplemental frame pivoted to the main frame, an offset roll mounted in the supplemental frame and adapted to coact with the platen, a second supplemental frame pivoted on the same axis as the first supplemental frame, a pattern roll mounted in said second supplemental frame, and an adjustable link tying together said two supplemental frames.
- 60 2. In a printing machine, the combination with a main frame, a platen mounted therein, a supplemental frame pivoted to the main frame, an offset roll mounted in the supplemental frame and adapted to coact with the platen, a second supplemental frame pivoted on the same axis as the first supplemental frame, a pattern roll mounted in said second supplemental frame, an adjustable link tying together said two supplemental frames, a third supplemental frame pivoted to the main frame, a pattern roll mounted in

the third supplemental frame and adapted to coact with the offset roll and an adjustable link connecting the axis of the second pattern roll to the axis of the offset roll.

3. In a printing machine, the combination of a main frame, a platen carried thereby, a supplemental frame pivoted to the main frame, an offset roll carried thereby, two supplemental frames pivoted to the main frame, one on the same axis as the offset roll frame and the other on a different axis, a pattern roll carried by each of the latter supplemental frames, adjustable means tying together the offset-roll-frame and that pattern roll frame which are pivoted on the same axis, and adjustable means tying together the offset roll axis and the axis of that pattern roll whose frame is pivoted on a different axis from the offset roll frame.

4. In a printing machine, the combination of a main frame, two supplemental frames pivoted to the main frame, a pattern roll carried by each supplemental frame, another supplemental frame pivoted to the main frame, an offset roll carried thereby, turnbuckles connecting said offset roll carrying frame with the frames carrying the two pattern rolls, eccentric shafts carrying the pattern rolls and operable to separate them from the offset roll, gears connecting the pattern rolls and offset roll and adapted to remain enmeshed notwithstanding the separation by said eccentric shafts, a platen with which the offset roll contacts in printing, and means for separating the offset roll from the platen without separating the pattern rolls from the offset roll.

5. In a printing machine, the combination with a main frame, a platen mounted therein, a supplemental frame pivoted to the main frame, an offset roll mounted in the supplemental frame and adapted to coact with the platen, a second pivotally mounted supplemental frame, a pattern roll mounted in said second supplemental frame, means tying together said two supplemental frames, a third pivotally mounted supplemental frame, a pattern roll mounted in the third supplemental frame and adapted to coact with the offset roll, means tying together the axis of the second pattern roll to the axis of the offset roll, and means for swinging said supplemental frames on their pivots, whereby both pattern rolls are maintained in contact with the offset roll during the separation of the offset roll from the platen.

6. In a printing machine, the combination of a main frame, a platen carried thereby, a supplemental frame pivoted to the main frame, an

offset roll carried thereby, two supplemental frames pivoted to the main frame, a pattern roll carried by each of the latter supplemental frames by means of an eccentric shaft to adjust the axis of the pattern roll with reference to its frame, turnbuckles tying together the offset roll frame with the pattern roll frames, a platen which the offset roll contacts in one position of the first-mentioned supplemental frame, means for adjusting the position of the frame carrying the offset roll and by means of the turnbuckles swinging the pattern rolls correspondingly, whereby the offset roll may be separated from the platen without changing the relation of the offset roll to either of the pattern rolls.

7. In a printing machine, the combination of a main frame, a platen mounted therein, a supplemental frame pivoted to the main frame, an offset roll carried by said supplemental frame, two additional supplemental frames pivoted to the main frame, a pattern roll carried by each of said last-named supplemental frames and coacting with said offset roll, means for adjusting the portion of the pattern roll frames at one end of each roll with reference to the portion of said frame at the other end of the roll to adjust the axis of each pattern roll with reference to the offset roll, means to move the supplemental frame carrying the offset roll to adjust the position of the offset roll relative to the platen, and rigid means interconnecting each of the other supplemental frames with the offset roll frame to maintain the distances between the axis of the pattern rolls carried thereby and the axis of the offset roll fixed during the movement of the offset roll frame.
